CHAIN FILING MACHINE

Ferdinand Armbrust and August G. Reibling,
Cranston, R. I., assignors to Armbrust Chain
Company, a corporation of Rhode Island

Application November 17, 1941, Serial No. 419,366

3 Claims. (Cl. 59—29)

Our present invention relates to chain machines and has particular reference to a machine for filing chains.

The principal object of the present invention is to provide a machine for filing chains, particularly ornamental chains, to produce a chain with the links filed flat.

A further object of the present invention is to provide an apparatus which will readily file an endless length of chain on both sides in a continuous process.

A further object of the present invention is to provide a filing machine which is simple in construction and easily and economically assembled.

Still another object of the present invention is to provide a filing machine which will last for a considerable period of time, and in which the abrasive portions of the machine will wear well.

With the above and other objects and advantageous features in view, our invention consists of a novel arrangement of parts, more fully disclosed in the detailed description following and more particularly defined in the claims appended thereto.

In the drawings:

Fig. 1 is a plan view of a machine embodying our invention, parts being omitted;

Fig. 2 is a side elevation thereof;

Fig. 3 is a view of a curb chain prior to filing;

Fig. 4 is a similar view after the chain has been filed;

Fig. 5 is a perspective view of the base of the tensioning device;

Fig. 6 is a perspective view of the cover therefor;

Fig. 7 is an end view of the machine embodying our invention;

Fig. 8 is a perspective view of the guide roll carriage;

Fig. 9 is a fragmentary view of the guide roll carriage support;

Fig. 10 is a partial section taken on line 10—10 of Fig. 1;

Fig. 11 is a perspective view of the friction roller;

Fig. 12 is a plan view of the helical guide; and

Fig. 13 is a perspective view of the polishing wheel.

Fig. 14 is a perspective view of a filing wheel.

In the manufacture of ornamental and other types of chains, it has been found advisable to add to the ornamentation of the chain by filing the links down on one or more sides to achieve a flattened effect. This filing is more particularly applied to curb chains. Heretofore, it has

been found necessary to file the chain by hand. The present invention is designed to provide an inexpensive readily assembled machine, which will file and polish an endless length of chain in one continuous operation and which will wear well.

Referring to the drawings illustrating our invention, and with particular reference to Figs. 1 and 2 thereof, the machine is preferably mounted on a base or table 20 of generally rectangular shape. The chain 21 is provided in an endless length and is fed into the apparatus from a source of supply not shown, preferably below the level of the base 20. The chain is fed into the machine from the upper lefthand corner, looking at Fig. 1 and passes over a guide rod 22, which is mounted on a bar 23, bolted to the edge of the table 20. The chain passes into a tensioning device 24, which is mounted on one side of the bar 23 and is adapted to frictionally releasably permit the chain to be pulled into the machine under tension. The chain passes across the table 20 and around an idling pulley 25, and over a guide pulley 26 which is mounted for both vertical and radial adjustment. The chain then passes under a filing wheel 27, which is adapted to rotate in a direction opposite the path of movement of the chain and thus file the top of the chain as it passes beneath the wheel. The chain then passes over a second guide pulley 28, mounted similarly to the pulley 26, and across to a friction roller 29, having a grooved surface 30 which is adapted to frictionally engage the chain as it is wound thereon. The roller 29 pulls the chain 21 through the machine counter to the movement of the filing wheel 27, the tensioning device 24 resisting the movement of the chain and providing for a suitable tension throughout the various stages of the machine.

40 A helical guide 31 is loosely mounted on the friction roller 29 to provide a spiral chain track, and causes the chain to follow a helical path on the roller 29 and come off the end of the roller after making enough turns to provide a friction grip.

45 A sufficient amount of the chain is now permitted to extend downwardly into a container or receptacle on the floor, and the chain is then fed across a second guide bar 32 positioned at the lower left-hand corner of the machine as shown in Fig. 1. The chain passes over the guide bar 32 with the already filed side on top. The guide bar 32 is fixed to a bar 33, bolted to the side of the table 20, similarly to the bar 23. The chain 50 now passes through a second tensioning device

34, similar to the tensioning device 24, across the table 20 and around rollers 35 and 36, similar to the rollers 25 and 26. This brings the unfiled side of the chain upwardly, and the chain now passes beneath the filing wheel 37, which is identical with the wheel 27, and also rotates in the direction opposite the path of movement of the chain. The chain passes over a roller 38, similar to the roller 28, and is wound on the friction roller 39 in a manner similar to the roller 29. The friction roller 39 is also provided with a loosely mounted helical guide 40 similar to the guide 31 and providing a spiral chain track.

To ensure an even filing of the chain and to prevent the filing wheels 27 and 37 from wearing along a fixed groove, a reciprocating motion is imparted to the chain as it passes beneath the filing wheels.

Construction

The detailed construction of the machine may now be described as follows: A source of motive power 41 is mounted to the right of the machine, as viewed in Fig. 2, and supported above the operative portions of the machine on legs or columns 42 on the table 20. The motor 41 drives a sprocket wheel 42 and chain 43, which drive a sprocket wheel 44 mounted on a shaft 45 on the table 20. The sprocket wheel 44 is of larger diameter than the wheel 42 to provide a reduction of the speed from the operating motor. The shaft 45 is rotatably mounted in journal bearings 46 and 47 on the table 20. Fixed to the shaft 45 is another sprocket wheel 48 of smaller diameter than the sprocket wheel 44 and connected by a chain 49 to a large sprocket wheel 50 mounted in the same plane as the sprocket wheel 48 but above the table 20, as shown in Fig. 2. The sprocket wheel 50 is mounted on a shaft 51 journalled at each end in bearings 52, which are in turn mounted on standards 53 on the table 20. Fixed to the outer end of the shaft 51 is a small sprocket wheel 54 which drives through a chain 55 to a larger sprocket wheel 56, which is mounted on a stud 57 on the standard 53. Mounted on the same stud 57 and rotatably secured to the sprocket wheel 56 is a small sprocket wheel 58 which drives through a chain 59 to a larger sprocket wheel 60, the sprocket wheel 60 being mounted at the end of a shaft 61 which is journalled in bearings 62 provided on the edge of the standards 53.

The drive from the motor to the shaft 45 therefore produces a slight reduction in speed, whereas the various chain and sprocket arrangements hereinabove described provide a much slower drive of the shaft 61.

The filing wheels 27 and 37 are mounted at each end of the shaft 45 and preferably comprise hardened steel disks or wheels each having a conventional, cross-grooved filing surface cut on its periphery. The direction of rotation of the shaft 45, the sprockets 44 and 48, and the filing wheels 27 and 37 are counter-clockwise as viewed in Fig. 2.

Referring to Figs. 7 to 10 inclusive, the bearings 46 and 47 are mounted on a journal mounting 63 which is provided on each side with spaced, laterally extending brackets 64. A guide roll carriage 65, preferably made in two sections and secured together, is mounted for reciprocating movement on the brackets 64 with its parallel side edges 66 passing over the brackets and being slidably secured thereto by overlapping plates 67, which are bolted to the brackets 64. The idling pulleys 25 and 35 are rotatably mounted on spaced extended portions 68, as shown in Figs. 1 and 10.

The bars 66 are connected by an end bar 69, and the pulleys 26 and 28, and 36 and 38, are respectively adjustably mounted, one at each end of the bar 69, by means of slotted arms 70. The carriage is reciprocated through an adjustable link 71, which is pivoted to the yoke 72 fastened to one of the bars 69, as shown in Figs. 7 and 8. The other end of the link 71 is pivoted to an eccentric 73, which is mounted at the end of a shaft 74 at the lower edge of the machine, as shown in Figs. 1 and 2. The shaft 74 is driven through gearing 75 and shaft 76, through the bevelled gearing 77 from the shaft 61. Rotation of the eccentric 73 causes the link 71 to reciprocate the carriage 65, which carries the chain beneath the filing rollers 27 and 37, and provides for movement of the chain across the entire face of both filing wheels.

The friction rollers 29 and 39 are both mounted on the shaft 61 so that they will rotate simultaneously and at the same speed. Loosely mounted on each are the helical guides 31 and 40, see Fig. 12, which comprise rectangular wiring bent into a helix of slightly larger diameter than the friction rollers to provide spiral chain tracks, the guides having one of their ends 78 extending downwardly to abut the edge of the table 20, as shown in Fig. 2, thus preventing rotation of the guides while the friction rollers are rotating.

The tensioning devices 24 and 34 are shown in detail in Figs. 2, 5 and 6. They each comprise a base portion 79 preferably of fiber having an upper longitudinal channel 80 through which the chain passes. A T-shaped cover 81 of the same material is placed over the base 79 with the central depending arm 82, which is slightly longer than the depth of the channel 80, extending into the channel. The cover 81 is held on the base 79 by threaded rods 83 which extend through the cover into the base, and which are provided with coil springs 84 between the top of the cover and nuts 84a on the rods, so that the cover may be resiliently adjustably held on the base. As the chain passes through the channel 80, it is resiliently and frictionally retarded by the depending portion 82 of the cover, which is spring pressed downwardly by the springs 84.

After the chain has been filed on both sides by the hereinabove-described machine, it is necessary to polish the filed surface to eliminate any roughness. For this purpose, we use a polishing wheel 85, see Fig. 13, which comprises a wheel base portion 85a of soft felt having its periphery impregnated with a mixture of emery wheel cement and emery powder to provide a polishing surface 86. The wheel may be provided with guide flanges 87 to prevent the chain from slipping from beneath the wheel.

To provide a continuous operation, a second machine, similar in construction with the one hereinabove described, is positioned adjacent the first machine the filing wheels 27 and 37 being replaced by the polishing wheels 85, so that as the chain leaves the roller 39, it can be fed directly into the polishing machine and the chain can thus be filed and polished in a continuous operation. However, if desired, the same machine can be used by removing the filing wheels 27 and 37 after the filing operation and replacing them with polishing wheels 85.

Operation

The detail operation of the machine may now be described as follows: The power from the motor 41 is transmitted to the shaft 45 by sprocket

wheel 42, chain 43, and sprocket wheel 44. This arrangement reduces the speed of rotation of the shaft 45. The drive is then taken off the shaft 45 by a small sprocket wheel 48 connected through a chain 49 to an intermediate large sprocket wheel 50, shaft 51, small sprocket wheel 54, chain 55, large sprocket wheel 56, small sprocket wheel 58, chain 59, large sprocket wheel 60 to the shaft 61. This reduces the speed of rotation of the shaft 61 as compared to the shaft 45 on which the filing wheels are mounted, so that the filing wheels rotate at a greater rate of speed than the movement of the chain beneath them. While various chain and sprocket wheel arrangements are shown, other reduction methods, such as worm and gears may be used.

As the chain is fed into the machine over the guide bar 22 and through the tensioning device 24, it passes slightly above the table 20, as shown in Fig. 2, and around the pulley 25, pulley 26, and under the wheel 27 and over the pulley 28. The chain is pulled through this portion of the machine by the friction roller 29 around which it is guided by the helical guide 31. Simultaneously with the movement of the chain beneath the filing wheel 27 the carriage 65 is reciprocated by the link 71, which is driven by the eccentric 73 through the shafts 74 and 76 by the shaft 61. The reciprocation of the carriage being in axial alignment with the filing wheel 27, the chain is moved back and forth beneath the filing surface of the wheel 27, so that the wheel will wear evenly and the filing action of the wheel will be aided by the movement of the chain across the surface. The chain now passes over the guide 32, through the tensioning device 34, again across the table 20, over rollers 35 and 36, and beneath the filing wheel 37, which files the other side of the chain. Inasmuch as the various pulleys 25, 26, 28 and 35, 36 and 38 are all mounted on the carriage 65, both sides of the chain will be simultaneously reciprocated beneath the filing wheels 27 and 37.

The chain passes over the pulley 38 onto the friction roller 39 which pulls the chain beneath the filing wheel 37, so that each frictional wheel is provided with its own friction roller, and the tension beneath one filing wheel is not transmitted nor does it affect the chain passing beneath the other filing wheel.

This completes the construction and operation of the apparatus embodying our invention. It can readily be seen from the foregoing that the apparatus is simple in construction and admirably adapted for its intended purpose. The use of applicants' hardened steel wheels with filing surfaces has been found by the applicants to be long wearing and more efficient than any other type of abrasive heretofore attempted. The applicants' drive arrangement permits ready ad-

justment of the tension on the chain passing through the machine, adjustment of the speed of drive of the chain which naturally fixes the amount that is filed from the chain, and provides a reciprocating movement which ensures an even wearing of the filing surface.

While we have described a specific embodiment of our invention, it is obvious that changes may readily be made in the size and shape and relative arrangement of the parts, in applicants' drive arrangement and chain pulling arrangement, and in the filing head, without departing from the spirit and the scope of the invention as defined in the appended claims.

We claim:

1. In a chain filing machine, a power shaft, a rotatable filing wheel, a chain tensioning device, a chain feeding wheel, and idler pulleys cooperating with said tensioning device and said feeding wheel to position a chain in filing contact with said filing wheel, said idler pulleys being rotatably mounted on a reciprocatable carriage, means operating said filing wheel from said power shaft, means operating said feeding wheel from said power shaft at a reduced speed relative to the filing wheel speed, and means for reciprocating said carriage to draw the chain across the face of the faster moving filing wheel.

2. In a chain filing machine, a power shaft, a rotatable filing wheel, a chain tensioning device, a chain feeding wheel having a spiral chain track, and idler pulleys cooperating with said tensioning device and said feeding wheel to position a chain in filing contact with said filing wheel, said idler pulleys being rotatably mounted on a reciprocatable carriage, means operating said filing wheel from said power shaft, means operating said feeding wheel from said power shaft at a reduced speed relative to the filing wheel speed, and means for reciprocating said carriage to draw the chain across the face of the faster moving filing wheel.

3. In a chain filing machine, a power shaft, a rotatable filing wheel, a chain tensioning device, a chain feeding wheel having a spiral chain track, and idler pulleys cooperating with said tensioning device and said feeding wheel to position a chain in filing contact with said filing wheel, said idler pulleys being rotatably mounted on a reciprocatable carriage, means operating said filing wheel from said power shaft to rotate in a direction opposite to the direction of feed of the chain, means operating said feeding wheel from said power shaft at a reduced speed relative to the filing wheel speed, and means for reciprocating said carriage to draw the chain across the face of the faster moving filing wheel.

FERDINAND ARMBRUST.
AUGUST G. REIBLING.
